RELASTING MACHINE

John T. Lancaster, Newton, Mass., assignor to
 United Shoe Machinery Corporation, Borough
 of Flemington, N. J., a corporation of New Jersey

Application March 14, 1940, Serial No. 323,957

31 Claims. (Cl. 12—15)

This invention relates to relasting machines and is herein illustrated and described as embodied in a relasting machine particularly adapted to operations upon hinged or otherwise collapsible lasts. The machine disclosed herein, in common with previous relasting machines, is provided with a support for the last, for example, a last pin, and with instrumentalities which act upon the shoe to urge the shoe upon the last.

It is an object of the invention to provide an improved relasting machine which is easy to operate and which, in its action, simulates a manual performance of the operation. In accordance with a feature of the invention, the illustrated relasting machine is provided with a pair of members mounted upon the ends of a lever and engageable, respectively, with the forepart of the shoe upper and with the heel end of the shoe bottom, in combination with means for swinging the lever to cause the forepart engageable member to straighten a collapsed last end and to cause the heel end engageable member to urge the heel end of the shoe upon the last. The fulcrum of the lever, as shown, may be substantially coaxial with the hinge of the last. The illustrated machine is further provided with a friction device constructed and arranged to be held in engagement with the shoe by the operator and to be moved by power-driven means to urge the shoe upon the last. This device, as disclosed herein, may consist of a pair of members which exert clamping pressure upon the opposite edges of the sole of the shoe. As further shown herein, the machine is further provided with a horn for guiding the heel end of the shoe upon the last. The movements of the various power-driven instrumentalities are coordinated by cams driven in unison and controlling the several instrumentalities.

These and other features of the invention, including details of construction and the arrangement of parts, will now be more particularly described with reference to the accompanying drawings, in which

Fig. 1 is a side elevation of the upper portion of the machine;

Fig. 2 is a front elevation of the parts shown in Fig. 1;

Fig. 3 is a side elevation of the horn-operating mechanism;

Fig. 4 is a plan view of the parts shown in Fig. 3;

Figs. 5, 6, and 7 are detail views of the sole edge gripping mechanism; and

Fig. 8 is a detail view of one of the cams.

The machine illustrated herein is provided with an upstanding last pin 10 for supporting a last L which, as shown, may be of the hinged type and upon which, while in collapsed condition, has loosely been placed a shoe S. The opposite edges of the forepart of the sole of the shoe are then clamped manually by the operator through a mechanism indicated generally by the reference character 12. A power-driven mechanism is then set into motion, which causes the device 12 to draw the shoe rearwardly upon the last and which then operates to cause a presser 14 to bear downwardly upon the heel seat of the shoe to urge the heel portion of the shoe on the last, while a pad 16 presses upwardly against the forepart of the shoe upper to straighten or extend the last. A horn 18 is provided for guiding the heel end of the shoe upon the last.

The supporting structure of the machine comprises a standard 20, in which is slidable for heightwise adjustment a column 22. Upon the upper portion of the column 22 is a head 24, which carries the operating instrumentalities of the machine.

The last pin 10 is threaded into a split socket 26 (Fig. 1) which is provided with a clamping bolt to enable the last pin to be secured in any desired position of heightwise adjustment. Formed upon the last pin 10 is a knurled flange 28 which facilitates turning for heightwise adjustment, and upon which rests the cone of the last. The socket 26 extends upwardly from a slide 30, which is held by a pair of gibbs 32 in a horizontal guideway formed in the head 24 and extending forwardly and rearwardly of the machine. Threaded into the forward end of the slide 30 is a screw 34 the unthreaded shank portion of which is freely rotatable in a bearing 36 secured to the head 24. A pair of collars 38 pinned to the shank of the screw 34 abut the opposite ends of the bearing 36 to hold the screw against endwise movement. A hand wheel 40 facilitates turning of the screw to adjust the last pin 10 forwardly or rearwardly.

The device 12 which grips the edges of the sole at the forepart of the shoe is carried by the forward ends of a pair of parallel rods 42 disposed on opposite sides of the shoe. The rearward end of each of the rods 42 telescopically engages a socket formed in an enlarged forward end portion 44 of a rod 46 (Fig. 1). A pin 48 passes through one of several pairs of diametrically opposite holes in each of the socket portions 44 and through one of several diametrical holes formed in each of the rods 42 to hold the rods in desired

positions of forward or rearward adjustment, which adjustment may be varied by removing the pins 48 and moving the rods 42 to the desired position and then replacing the pins 48 through different sets of registering holes. For each of the rods 46 there is provided a block 50 through which the rod is freely slideable. Secured to each of the rods 46 at its rear end is a collar 52 and surrounding each of the rods between the block 50 and the collar 52 is a coil compression spring 54. The spring 54 urges the rods rearwardly as far as permitted by the shoulders of the socket portions 44 engaging the blocks 50. Each of the blocks 50 is freely pivoted upon the upper end of a lever 58, the common axis of the pivotal mounting of the blocks 50 being horizontal and transverse with respect to the machine. Each of the levers 58 is secured upon a shaft 60 journaled in the head 24 to serve as a fulcrum, the axis of this shaft being also horizontal and transverse with respect to the machine. The two levers 58 and the shaft 60 turn as a unit, the levers being always parallel. One of the levers 58 extends downwardly beyond its fulcrum and at its lower end carries a cam roll 62 through which the lever is operated by mechanism later to be described to swing the levers 58 about the axis of the shaft 60 and thereby to cause the sole edge gripping device 12 to be urged rearwardly.

30. The sole edge gripping device comprises a bar 64 (Figs. 5, 6 and 7) extending horizontally and transversely of the machine across the forward ends of the rods 42. In a suitable bearing formed in the forward end of each of the rods 42 is mounted a pin 66, the two pins 66 being coaxial. Secured upon each of the pins 66 is a block 68. In one of the blocks 68 is mounted a pin 70 having an unthreaded shank portion extending through the block 68 and having pinned upon its lower end portion a collar 72 (Fig. 6) for engaging the under surface of the block 68 to hold the pin 70 against endwise movement. The upper portion of the pin 70 extends through a slot 74 (Fig. 5) formed in the end portion of the bar 64 and is threaded to receive a clamping nut 76 which may be turned through a handle 78 to clamp the bar 64 in any desired position of transverse adjustment with respect to the rods 42. A pin 80 secured in the bar 64 and extending slideably through a diametrical hole in the pin 70 holds the pin 70 against turning. The other block 68 is provided with an upstanding unthreaded pin 82 which extends through a slot 84 formed in the bar 64, the pin 82 being held against endwise movement relatively to the block and the bar by a head 86 upon its lower end and a rectangular block 88 secured upon its upper end portion. The block 88 is slideable in the slot 84 and has a shouldered top portion which rides on the upper surface of the bar 64.

60. In the central portion of the bar 64 is rigidly secured an upstanding pin 90 upon which is rotatably mounted a sleeve 91 (Figs. 5 and 6). Extending diametrically from the sleeve 91 in opposite relation to each other are a pair of arms 94 and 96 respectively, having rounded bearing surfaces which engage openings formed in a pair of slides 98 and 100 respectively. The sleeve 91 is turned by a handle 92 having a hub 93 which is rotatably mounted on the pin 90 and which has a tongue-and-slot connection 95 (Fig. 6) with the sleeve 91. The slides 98 and 100 are slideable longitudinally along the bar 64, being guided by finished surfaces on the upper surface 75 of the bar 64 and on the inner sides of a pair of

lugs 101 extending upwardly from the marginal portions of the bar. The sleeve 91 serves as a bearing for the inner edges of both slides. A cover plate 102 secured by screws 104 to the lugs 101 retains the slides in their guideways. The cover plate 102 has an opening which serves as a bearing for the reduced lower portion of the hub 93. Secured upon the upper end of the pin 90 is a collar 103 for retaining the hub 93. Each of the slides 98 and 100 is provided with a hub 105 which extends downwardly through a longitudinal slot 108 in the bar 64, the hubs and their respective slots being positioned along the longitudinal center line of the bar 64 on opposite sides of the pin 90. The diameters of the hubs 105 are equal to the widths of the slots 108, allowing for clearance, and the slots thus assist in guiding the movements of the slides 98 and 100. Extending downwardly through each of the hubs 105 is a pin 106, and on the lower end of each of the pins 106 is pivotally mounted a clamping block 110 having a leather pad 112 adapted to engage an edge of the sole of the shoe S. The two pads engage the opposite edges of the sole respectively and it is evident that turning of the handle 92 by the operator will tend to tighten or loosen the clamps on the edges of the sole. Secured to the under surface of a widened central portion 113 of the bar 64 is a pad 114 which engages the shoe bottom to support the sole against buckling in case of excessive clamping pressure upon its edges.

The edge gripping mechanism 12 may not always be necessary, as some shoes may fairly easily be drawn over the forepart of the last by hand. 35 In such case the edge gripping mechanism may be latched up out of the way by a pair of plungers 116 (Fig. 2) which support the rods 42 respectively. These plungers are slideable in a pair of stationary brackets 118 (Figs. 1 and 2) secured upon parallel upwardly extending portions 120 of the head 24. The plungers have rounded ends for engagement with the rods 42 and are urged inwardly to latching position by a pair of leaf springs 122 secured to the brackets 118 respectively. 40 These springs enable the plungers to yield when the edge gripping mechanism is forcibly snapped into or out of latching position by hand. 45

The pad 16 which presses upwardly against 50 the forepart of the shoe upper to straighten the last is mounted at the forward end of a frame member 124 (Figs. 1 and 2) having approximately the shape of a hollow rectangle. The frame member 124 is fulcrumed upon a pair of 55 coaxial trunnion pins 126 mounted in the extensions 120 of the head 24. The axis of the trunnions 126 extends horizontally and is transverse with respect to the machine. The pad 16 comprises a roll cushioned with rubber and idly 60 rotatable to distribute wear over its entire periphery. Extending downwardly from the hollow frame 124 is an arm 128 through which the frame may be rocked. Pivotal connecting the lower end of the arm 128 with an operating lever 130 is a link 132. For guiding the lever 128 a pair of finished surfaces 133 (Fig. 1) are provided on the inner sides of the frame extensions 120. The lever 130 is loosely fulcrumed upon the shaft 60 and extends downwardly below the fulcrum. Upon the lower end of the lever 130 is mounted a cam roll 134 through which the lever 130 is operated by mechanism later to be described. In the upper end portion of the lever 130 is formed an arcuate slot 135 (Fig. 1) which 75

is concentric with the pivotal connection of the link 132 with the arm 128. A pin 138 which may be clamped to the lever 130 in any desired position of adjustment along the slot 136 by a nut 140 5 constitutes the pivotal connection of the link 132 to the lever 130. By adjusting the pin 138 in the lever 130 the throw of the frame 124 may be increased or diminished.

The presser 14 which urges the heel seat of 10 the shoe downwardly upon the last comprises a U-shaped rubber pad carried by a block 142 having a convex cylindrical surface which bears against a concave cylindrical surface formed in a support 144 having a pair of arcuate ears 146 15 and an upwardly extending shank 148. The block 142 is secured between the ears 146 by a pair of pins 158 extending from the block through arcuate slots formed in the ears. The shank 148 extends upwardly through a bearing 154 carried 20 in the upper forward end of an arm 156. Threaded into the bearing 154 is a bushing 158 through which the shank 148 is freely slideable. A coil compression spring 160 surrounding the shank 148 is interposed between the support 144 25 and the lower end of the bushing 158. A knurled head 161 on the bushing 158 facilitates turning to adjust the compression of the spring 160. Threaded upon the upper end portion of the shank 148 is a nut 162 which limits the relative 30 downward movement of the member 14 against the pressure of the spring 160. A pin 164 secured to the support 144 and freely slideable in a bearing 166 formed in the arm 154 prevents rotation of the pad 14 about the axis of the shank 35 146. The arm 156 is fulcrumed upon a pin 168 carried in the upper rearward portion of the frame 124. Secured upon opposite ends of the pin 168 are a pair of parallel rocker arms 170 which extend downwardly below the pin 168. 40 Each of the arms 170 carries at its lower end a roll 172 (Fig. 2). Formed upon a side of each of the arms 58 is an arcuate guideway 174 which determines the path of movement of one of the rolls 172. When the arm 52 occupies its rear- 45 most position the centers of the arcs of the guideways will lie in the axis of the pins 126.

The horn 18 has a tail 176 (Figs. 1 and 3) terminating in a pair of spaced ears 178 which are pivotally mounted upon a pin 180 to provide for 50 free swinging movement of the horn about the pin. The pin 180 is secured by a set screw 182 in an eye hole formed in the end of a bar 184. A torsion spring 186 having one end secured in the pin 180 and the opposite end secured in one of the ears 178 urges the horn in a counterclockwise direction as viewed in Figs. 1 and 3. A collar 188 formed on the rod 184 engages a member 55 later to be described to limit rotation of the horn 18 under the influence of the spring 186, the normal operating position of the horn 176 being inclined about 30° upwardly from the axis of the bar 184. The bar 184 is slidably mounted in a 60 guideway formed in a block 190 which, in turn, is slidably mounted in a support 192. A compression spring 194 surrounding the bar 184 and interposed between the collar 188 and the block 190 urges the bar 184 to the left to a stop position determined by the engagement of a collar 196, pinned upon the opposite end of the bar 184, with the block 190. The support 192 is pivotally 65 mounted for free tilting movement upon a pin 198 secured in a stationary bracket 200 mounted upon a rearward extension of the head 24. A block 202 surmounting the support 192 and secured 70 thereupon retains the slide block 190 in its 75 cured

guideway. Housed within a longitudinal bore in the block 202 is a compression spring 204, one end of which abuts a closed end of the bore, and the other end of which abuts a screw 206 threaded into the block 190 and extending through a longitudinal slot 208 formed in the base of the block 202. The spring 204 is no stronger than is necessary to enable it to overcome friction in moving the block 190 together with the bar 184 to the left, as seen in Figs. 1 and 3. Pivotedly mounted 10 upon the pin 198 is a lever 210 having a gear sector 212 concentric with the pin 198. Secured in the outer end of the lever 210 is a pin 214 upon which is pivotally mounted a block 216 which is slidably mounted for movement at right angles 15 to that of the bar 184 in a guideway formed in the support 192. The pin 214 is loose enough to accommodate the slight arcuate movement, and extends through a slot 217 in the support 20 192. Formed in the block 216 are rack teeth 218 adapted to mesh with corresponding rack teeth 220 formed in the under surface of the block 190. Secured in the block 192 and extending downwardly therefrom is a pin 222 surrounded by a spring 230 which is interposed between the under 25 surface of the lever 210 and a nut 232 threaded, for adjustment of the spring compression, upon the pin 222 and secured by a lock nut. Meshing with the gear segment 212 is a gear segment 234 formed upon a lever 236 which is mounted for 30 free pivotal movement upon the shaft 60 and which, at its lower end, carries a cam roll 238 (Fig. 2). A cam which will later be described operates this mechanism and is arranged to maintain the lever 236 in an initial position such as to cause the lever 210 to bear downwardly and to compress the spring 230 while rotation of the block 192 in a clockwise direction is prevented by the engagement of a lug 240 (Fig. 4) on the support 192 with a stop 242 formed on the bracket 40 200.

Secured between a rearward extension of the ears 178 is a pin 244 (Fig. 3) upon which is pivotally mounted one end of a link 246, the opposite end of which link is pivotally connected 45 through a pin 248 to a link 250. The opposite end of the link 250 is pivotally mounted for free swinging movement upon a pin 252 secured in the support 192. Tilting of the support 192 through the cam mechanism later to be described 50 will bring the pin 248 downwardly. Extending across the path of the pin 248 in such downward movement is a pin 254 having at each end an eccentric 256 one of which eccentrics is shown in Fig. 3. The eccentrics 256 are mounted in the 55 arms 58, respectively, and may be turned to effect adjustment of the pin 254 to vary the time of engagement by the pin 248. It is evident that downward swinging movement of the support 192 in causing the pin 248 to engage the pin 254 will 60 straighten the links 246 and 250 and thereby rotate the horn in a clockwise direction about the pin 180. The links 246 and 250 are arranged to enable the pin 248 to pass upwardly just beyond 65 dead center and thereby to insure against the horn 176 returning to its earlier position when the support 192 tilts upwardly again. To insure such return of the horn to normal position, there is provided a stop member 258 secured upon the 70 bracket 200. The pin 248 will engage the stop 258 before the support 192 has completed its upward movement thereby drawing the pin 248 below dead center and enabling the spring 186 to swing the horn in a counterclockwise direction to 75

its initial position. It has already been stated that the collar 188 operates as a stop to limit rotation of the horn under the influence of the spring 186. The collar 188 performs this function by engaging the link 246 between the ears 178.

- 10 The cam mechanism, already mentioned, comprises a cam disc 260 (Figs. 1 and 2) having formed in its face a groove 262 in which is seated the roll 134 which operates to swing the frame 124 about the fulcrum 126, and also a cam disc 264 (Figs. 8 and 2) having a pair of grooves 266 and 268 cut in opposite faces respectively. Seated in the groove 266 is the cam roll 62 which operates 15 in the groove 268 is the cam roll 238 which operates the horn mechanism. The cam disc 260 and 264 are fixed upon a shaft 270 which is journaled in suitable bearings carried by the head 24.
- 20 The cam shaft 270 is driven through a one revolution clutch from a gear 272 (Figs. 1 and 2) mounted for free rotation on the shaft 270 and continuously driven by a gear 274 formed on the hub of a pulley 276. The pulley 276 is mounted 25 for free rotation on the shaft 68, and is driven through a belt 278 from any convenient source of power. The one revolution clutch above-mentioned may be of any well-known type, and comprises a treadle rod 280 and a tripping lever 282.
- 30 A spring 284 normally holds up the treadle (not shown).

In operating the machine, the shoe S is first drawn over the last L by hand as far as convenient and the last is then mounted on the last pin 10. 35 It is desirable to bring the hinge of the last into substantially coaxial relation with the trunnion pins 126 and this can be accomplished by turning the wheel 49 and also by turning the knurled head 28. The operator then takes the edge 40 gripping mechanism 12, which he pulls down from its out-of-the-way position and clamps the edges of the sole of the shoe between the gripping members 110. Such clamping is accomplished by turning the handle 92 manually with as great 45 or little pressure as may be desired. The operator thereupon depresses the treadle to initiate the automatic operation of the machine, meanwhile holding the handle 92 in clamping position. The first operation performed by the cam 50 mechanism is to rock the levers 58 in clockwise direction, thereby compressing the springs 54 and causing the edge gripping mechanism 12 to draw the forepart of the shoe completely on the last. In the case of shoes which fit the last somewhat 55 loosely, it may sometimes be more convenient to perform this part of the operation by hand, leaving the edge gripping mechanism 12 in its out-of-the-way position. As the upper portion of the lever 58 swings to the right, as seen in Fig. 1, the rolls 172 will be moved in the same direction rocking the arm 156 in a counterclockwise direction and bringing the heel seat pad 14 down close to the heel seat of the shoe. Further 60 rotation of the cam shaft will not for the time being change the position of the arms 58 but will rock the arm 130 in a counterclockwise direction. This will operate through the link 132 to swing the frame 124 in a clockwise direction about the trunnion 126, causing the pad 16 to push upwardly against the shoe upper to straighten the last while the heel seat pad 114 pushes downwardly to urge the heel portion of the shoe upon the last. The movement of the pad 16 is sufficient to start the straightening of the last and 70 to overcome the initial tendency of the last 75

mechanism to hold the last in broken condition. Most lasts will then snap into straightened position as a result of the action of the internal mechanism with which they are provided. The pad 16 does not follow the forepart of the shoe 5 and the last throughout their complete straightening movement, however, but stops to provide a sufficient clearance to insure against damaging the last. This same swinging movement of the frame 124 will cause the heel seat pad 14 to be 10 brought down far enough to urge the heel seat of the shoe against the last while the rolls 172 travel down the arcuate guideways 174 of the now stationary arms 58. These guideways, being concentric with the fulcrum pins 126, hold the 15 arm 156 in fixed relation to the swinging frame 124. As the pad 14 presses downwardly against the heel seat, the spring 160 may yield to accommodate excess movement. The cylindrical bearing surfaces between the block 142 and the support 144 enable the pad to assume whatever angle 20 may be imposed upon it by engagement with the shoe.

When the last is being mounted upon the last pin, the heel end of the last will push the horn 25 18 and its associated mechanism back against the pressure of the weak spring 204 without changing the 30° angle of the horn which is maintained by the relatively strong torsion spring 186. The horn will thus assume its proper initial 30 position, regardless of the length of the last. As the heel portion of the shoe is urged downwardly, it will come outside of the end of the horn. Now as the heel portion of the shoe descends, the cam mechanism will rock the arm 210 in a counterclockwise direction, as seen in Fig. 3, enabling the spring 230 to cause the rack teeth 218 to engage the rack teeth 220 and lock the slide 190 in its guideway in the block 192. Further rotation of the arm 210 will swing the housing 192 in a 40 counterclockwise direction, moving downwardly the pin 180 which supports the horn in an arc about the axis of the pin 198. This movement will draw the horn downwardly between the shoe and the last while the torsion spring 186 will 45 yield to enable the horn to rock about the corner of the last. As the horn is gripped tightly between the shoe and the last, the spring 194 may yield to enable the horn to assume whatever angle is imposed upon it by the shoe and the last. Continued movement of the cam mechanism thus 50 withdraws the horn from between the shoe and the last and brings the pin 248 into contact with the pin 254. The arms 58 which support the pin 254 are at this time stationary. The toggle 55 links 246 and 250 are thereupon straightened and brought slightly beyond dead center to swing the horn into a substantially upright position out of the way of the shoe. Continued rotation of the cam 264 then causes the block 192 to swing in a 60 clockwise direction and to return to its initial position at the later stages at which movement the pin 248 engages the stop 258 to break the toggle formed by the links 246 and 250, whereupon the torsion spring 186 returns the horn 18 65 to its initial angular position. During this time, the rotation of the cams serves also to restore the frame 124 and the pad 14 to their initial positions and also the arms 58. The automatic clutch mechanism then operates to bring the 70 machine to rest ready for another operation.

Having thus described my invention, what I claim as new and desire to secure by Letters Patent of the United States is:

1. A relasting machine comprising a support 75

for the heel end of a hinged last, means for urging a shoe rearwardly on the last, means for exerting pressure upon the forepart of the shoe to straighten the last, and means for exerting pressure upon the heel end of the shoe bottom to urge the heel end of the shoe upon the last.

2. A relasting machine comprising a last pin for supporting the heel end of a hinged last, means for urging the forepart of a shoe rearwardly on the last, a lever fulcrumed upon an axis which is substantially transverse with respect to the last, a member on one end of said lever engageable with the forepart of the shoe upper, a member on the opposite end of said lever engageable with the heel end of the shoe bottom, and means for swinging said lever to cause the first mentioned shoe-engaging member to press against the shoe to straighten the last and to cause the second mentioned shoe-engaging member to urge the heel end of the shoe upon the last.

3. A relasting machine comprising a support for the heel end of a hinged last, said last being partially inserted in a shoe, a lever fulcrumed for tilting movement about an axis which is substantially transverse with respect to the last, members on the ends of said lever engageable with the forepart of the shoe upper and with the heel end of the shoe bottom respectively, and means for swinging said lever to cause the forepart-engageable member to straighten the last and to cause the heel-end-engageable member to urge the heel end of the shoe upon the last.

4. A relasting machine comprising a last pin for supporting the heel end of a hinged last, said last being partially inserted in a shoe, a lever, a fulcrum for said lever substantially coaxial with the hinge of the last on said last pin, members on the ends of said lever engageable with the forepart of the shoe upper and with the heel end of the shoe bottom respectively, and means for swinging said lever about said fulcrum to cause the forepart-engageable member to straighten the last and to cause the heel-end-engageable member to urge the heel end of the shoe upon the last.

5. A relasting machine comprising a support for the heel end of a hinged last, said last being partially inserted in a shoe, a lever fulcrumed for tilting movement about an axis which is substantially transverse with respect to the last, a member on one end of said lever engageable with the forepart of the shoe upper, a member engageable with the heel end of the shoe bottom and pivotally mounted upon the opposite end of said lever for swinging movement from an out-of-the-way position into an operative position over the heel end of the shoe bottom, means for holding said heel-end-engageable member in said operative position on said lever, and means for swinging said lever to cause the forepart-engageable member to straighten the last and to cause the heel-end-engageable member to urge the heel end of the shoe upon the last.

6. A relasting machine comprising an upright last pin for supporting in inverted position the heel end of a hinged last, said last being partially inserted in a shoe, a lever fulcrumed for tilting movement about an axis which is substantially transverse with respect to the last, a member on one end of said lever engageable with the forepart of the shoe upper, a member pivotally mounted upon the opposite end of said lever and engageable with the heel end of the shoe bottom, means for swinging said heel-end-engageable

member about its pivotal mounting from an out-of-the-way position into an operative position over the heel end of the shoe bottom, and means operable in timed relation to the first-mentioned swinging means for swinging said lever to cause the forepart-engageable member to straighten the last and to cause the heel-end-engageable member to urge the heel end of the shoe upon the last.

7. A relasting machine comprising a last pin for supporting the heel end of a hinged last, said last being partially inserted in a shoe, a lever fulcrumed for tilting movement about an axis which is substantially transverse with respect to the last, a member on one end of said lever engageable with the forepart of the shoe upper, a member pivotally mounted upon the opposite end of said lever and engageable with the heel end of the shoe bottom, a pair of cams connected for rotation in unison about a common axis, a connection operated by one of said cams for swinging said heel-engageable member about its pivotal mounting from an out-of-the-way position into an operative position over the heel end of the shoe bottom, and a connection operated by the other cam for swinging said lever to cause the forepart-engageable member to straighten the last and to cause the heel-end-engageable member to urge the heel end of the shoe upon the last.

8. A relasting machine comprising a support for a last partially inserted in a shoe, a member engageable with the heel end of the shoe bottom, a carrier upon which said shoe-engageable member is pivotally mounted for movement from an out-of-the-way position into an operative position over the heel end of the shoe bottom, means for holding said member in said operative position, and means for moving said carrier to cause the shoe-engageable member to urge the heel end of the shoe upon the last.

9. A relasting machine comprising a support for a last partially inserted in a shoe, a member engageable with the heel end of the shoe bottom, a carrier upon which said shoe-engageable member is pivotally mounted for movement from an out-of-the-way position into an operative position over the heel end of the shoe bottom, cam operated mechanism for moving into and for holding in operative position said shoe-engageable member, and cam operated mechanism for moving said carrier to cause the shoe-engageable member to urge the heel end of shoe upon the last.

10. A relasting machine comprising a support for a last partially inserted in a shoe, a member engageable with the heel end of the shoe bottom, a lever upon which said shoe-engageable member is pivotally mounted for movement from an out-of-the-way position into an operative position over the heel end of the shoe bottom, a fulcrum for said lever, said lever having an arm whereby the lever may be swung about its fulcrum, and said shoe-engageable member having an arm whereby the shoe-engageable member may be swung about its pivotal connection to said lever, a pair of driven cams, and driving connections between said cams and said respective arms for swinging said shoe-engageable member and for swinging said lever to cause the shoe-engageable member to urge the heel end of the shoe upon the last.

11. A relasting machine comprising a last pin for supporting a hinged last partially inserted in a shoe, a member engageable with the bottom of

- the heel end of the shoe, a lever upon which said shoe-engageable member is mounted, a fulcrum for said lever substantially coaxial with the hinge of the last, a driven cam, and connections 5 through which said cam swings said lever to cause said shoe-engageable member to press against the shoe bottom to urge the heel portion of the shoe upon the last.
12. A relasting machine comprising a support 10 for a hinged last, a member engageable with the upper of the forepart of a shoe on the last, a driven cam, and connections through which said cam causes said member to press against the forepart of the shoe to straighten the last.
13. A relasting machine comprising a last pin 15 for supporting a hinged last, a member engageable with the upper of the forepart of a shoe on the last, a lever upon which said shoe-engageable member is mounted, a fulcrum for said lever substantially coaxial with the hinge of said last, a driven cam, and connections through which said cam swings said lever to cause said shoe-engageable member to press against the forepart of the shoe to straighten the last.
14. A relasting machine comprising a support 20 for a last partially inserted in a shoe, a member frictionally engageable with the shoe on said last, a device constructed and arranged to enable the operator to press said member against the shoe, and power-driven means for moving said member while thus pressed against the shoe to urge the shoe upon the last.
15. A relasting machine comprising a support 25 for a last partially inserted in a shoe, a pair of members frictionally engageable with a portion of the shoe on said last, a device constructed and arranged to enable the operator to exert a clamping pressure between said members upon said portion of the shoe, and power driven means for moving said members while thus clamped by the operator to urge the shoe upon the last.
16. A relasting machine comprising a last pin 30 for supporting a last, a pair of friction members engageable with the opposite edges respectively of the sole of a shoe on said last, a device constructed and arranged to enable the operator to exert clamping pressure between said members upon the sole, and power driven means for moving rearwardly said members thus clamped to urge the forepart of the shoe rearwardly upon the last.
17. A relasting machine comprising a last pin 35 for supporting a last, a pair of friction members engageable with the opposite edges respectively of the sole of a shoe on said last, a pair of slides upon which said friction members are respectively mounted, a carrier in which said slides are mounted for movement transversely of the shoe, a device constructed and arranged to enable the operator to move said slides in said carrier to clamp the sole between said friction members, and means for moving said carrier rearwardly of the shoe to cause the friction members through 40 their clamping engagement with the sole to urge the forepart of the shoe rearwardly upon the last.
18. A relasting machine comprising a support 45 for a last, a pair of friction members engageable with the opposite edges respectively of the sole of a shoe on said last, a device for clamping the sole between said friction members, mechanism for moving said device rearwardly to cause the friction members to urge the forepart of the shoe upon the last, and a connection between said 50 device and said mechanism constructed and arranged to enable the device to move freely laterally of the shoe and thereby to center itself when the friction members are clamped upon the sole.
19. A relasting machine comprising a support 55 for a last, a pair of friction members engageable with the opposite edges respectively of the sole of a shoe on said last, a device for clamping the sole between said friction members, a pair of rods connected to said device and extending rearwardly therefrom upon opposite sides of the shoe, a pivotally mounted arm, a driving connection between the rear ends of said rods and said arm, and a driven cam constructed and arranged to swing said arm to move the device rearwardly, thereby causing the friction members to urge the forepart of the shoe upon the last.
20. A relasting machine comprising a support 60 for a last, a pair of friction members engageable with the opposite edges respectively of the sole of a shoe on said last, a device for clamping the sole between said friction members, a pair of parallel rods connected to said device and extending rearwardly therefrom upon opposite sides of the shoe, a pair of blocks in which said rods are slidably mounted, a collar on the rearward end of each rod, a coil compression spring surrounding each rod and interposed between the block and the collar of that rod, a pivotally mounted arm, coaxial pivotal connections between said blocks and said arm to enable the rods to swing heightwise, and a cam constructed and arranged to swing said arm to move the device rearwardly to cause the friction members to 65 urge the forepart of the shoe upon the last.
21. A relasting machine comprising a support for a last partially inserted in a shoe, a device engageable with the forepart of the shoe, a member engageable with the heel end of the shoe bottom, a horn interposable between the heel end of the last and the interior of the shoe, three cams driven in timed relation to each other, means operated by one of said cams for causing said forepart engageable device to urge the forepart of the shoe rearwardly on the last, means operated by another of said cams for causing said heel-end-engageable member to press the heel end of the shoe upon the last, and means operated by the remaining cam for rocking the horn about the heel end of the last to guide the heel end of the shoe upon the last.
22. A relasting machine comprising a support 70 for a last partially inserted in a shoe, two devices engageable with the forepart of a shoe, two cams driven in timed relation to each other, means operated by one of said cams to cause one of said devices to urge the forepart of the shoe rearwardly upon the last, and means operated by the other cam to cause the other device to press against the forepart of the shoe to straighten the last.
23. A relasting machine comprising a support 75 for the heel end of a hinged last, said last being partially inserted in a shoe, a member engageable with the forepart of a shoe, a member engageable with the heel portion of the shoe, a driven cam, and means operated by said cam for causing said forepart engageable member to press against the forepart of the shoe to straighten the last and for causing the heel-portion-engageable member to urge the heel portion of the shoe upon the last.
24. A relasting machine comprising a support 80 for a last partially inserted in a shoe, a horn for 75

guiding the heel end of the shoe upon the last, a carrier for said horn, a guide in which said carrier is slidably mounted, a spring urging said carrier in said guide to hold the horn yieldingly against the last, and means for moving said carrier to cause the horn to rock around the heel end of the last to guide the heel end of the shoe upon the last.

5 25. In a relasting machine, a horn for guiding the heel end of a shoe over a last, yieldable means for holding said horn in a predetermined angular position, and yieldable means for urging said horn against the heel end of the last, said holding means being stronger than said urging means 10 to insure the horn maintaining said angular position upon engaging the last.

10 26. In a relasting machine, a support for a last, a horn, a carrier upon which said horn is pivotally mounted, yieldable means for holding said horn 15 in a predetermined angular position with respect to said carrier, yieldable means acting upon said carrier to urge the horn against the heel end of the last to determine an initial operating position of the horn, said urging means being weaker than 20 said holding means to insure the horn maintaining said angular position in said initial operating position, and means for moving said carrier to cause the horn to perform an operative movement 25 to guide a shoe upon the last.

20 30 27. In a relasting machine, a support for a last, a horn, a slide upon which said horn is pivotally mounted, a guide for said slide, yieldable means for holding said horn in a predetermined angular position with respect to said slide, yieldable means 35 acting upon said slide to urge the horn into an initial operating position wherein the horn engages the heel end of the last, said holding means being stronger than said urging means to insure said horn maintaining said angular position upon 40 engaging the last, means for locking said slide in said guide when the horn is in said initial operating position, and means acting upon said guide to cause the horn to perform an operative movement 45 in guiding a shoe upon the last.

45 28. In a relasting machine, a horn, a pivotal

mounting for said horn, yieldable means for holding said horn in a predetermined angular position about said mounting, a contractile support for said pivotal mounting, a spring for resisting contraction of said support, a fulcrum upon which 5 said support is pivotally mounted, and means for swinging said support about said fulcrum to cause said horn to perform an operative movement in guiding a shoe upon a last.

29. In a relasting machine, a support for a last, 10 a horn, a slide upon which said horn is pivotally mounted, yieldable means for holding said horn in a predetermined angular position with respect to said slide, a guideway for said slide, a pivotal mounting for said guideway, means for tilting 15 said guideway about said pivotal mounting to cause the horn to perform an operative movement in guiding a shoe upon a last, and a spring for urging said slide along said guideway to hold the 20 horn against the last.

30. In a relasting machine, a horn, yieldable means for holding said horn in a predetermined angular position, means for causing said horn to perform an operative movement in guiding a shoe upon a last, and means for swinging said horn 25 away from said angular position in opposition to said holding means to enable the horn to perform a return movement without striking the last or shoe.

31. In a relasting machine, a support for a last, 30 a horn for guiding the heel end of a shoe over the last, a support upon which said horn is pivotally mounted for swinging movement, a spring arranged to swing said horn about said support, a stop for holding said horn at a normal angular 35 position under the influence of said spring, means for operating said support to cause the horn to perform a guiding movement in the course of a relasting operation and for then returning the horn to initial opposition, during which guiding movement said spring may yield, and means for swinging said horn in opposition to said spring 40 to prevent the horn from striking the last or shoe in its return movement.

JOHN T. LANCASTER. 45
